UNITED STATES PATENT OFFICE.

DANIEL R. BACON, OF GOSHEN, NEW YORK, ASSIGNOR TO PEREY MANUFACTURING COMPANY, INC., OF NEW YORK, N. Y., A CORPORATION OF NEW YORK.

TURNSTILE.

Application filed November 7, 1922. Serial No. 599,541.

This invention relates to turnstiles in general and particularly to a kind to be transferred from one place to another.

The main object of this invention is to provide in combination with a stationary turnstile casing, stand or standard, a removably mounted head containing all operating mechanisms generally connected with a turnstile.

10 Another object of my invention is to provide in connection with the head, spring controlled operating arms adapted to facilitate an easy working of the device.

15 Another object of my invention is to provide an automatic locking device adapted to be released through the operation of said arms.

20 Another object of my invention is to provide within such removable head, a detent mechanism adapted to automatically position the movable part of the head in a predetermined relation to the stationary part thereof.

25 Another object of my invention is to provide within such head a one-way clutch adapted to permit the operation of the arms in one direction while preventing the operating of the arms in the opposite direction.

30 A further object of my invention is to provide, in connection with the head, and corresponding to a provision made upon the standard, a fastening device for quickly, temporarily but securely attaching the head to such standard.

The present invention is primarily designed for use in street-cars and particularly for cars making a certain limited trip between two distant points and returning on

40 the same line from one point to the other. Existing devices of this kind have mostly been made stationary at both ends of the car, and several attempts have been made to

45 make a removable upper portion of the turnstile which may be transferred from one end to the other by attaching it to fixedly placed stands at both ends of the car. These stands have mostly contained all mechanism, as for instance, a release operated by the conductor, a counter, a one-way clutch and other devices necessary for the operation of the turnstile. The only portion moved from

standard to standard was the heads with arms. My device differs from the heretofore used appliances by including not only 55 all operating mechanisms of the turnstile but also a counter permanently associated with the transferable head.

The foregoing and further objects will be more fully apparent from the following description and the accompanying drawings forming part of this specification, in which:

Figure 1 represents a preferred form of my device in connection with a standard partially broken off.

65 Figure 2 is a sectional detailed view taken on line 2—2 of Figure 1.

Figure 3 is an enlarged partial side elevation of the arm-locking device.

70 Figure 4 is a top view of the counter mechanism.

Figure 5 is a cross-sectional view taken on line 5—5 of Figure 2.

75 Referring to the drawings, numeral 1 denotes a stand, standard or casing of a turnstile comprising a tubular body 2, provided at its upper portion with a lug 3. Adapted to be inserted into the upper portion of the standard is an annular extension 4 of the removable head 5. From the latter extends 80

downwardly a double lug 6, through which passes a set screw or a similar device 7, registering with an aperture 8 of lug 3 of the casing, and by which means the head extension 4 is rendered immovable. Extending 85

sidewardly from, and adapted to oscillate, is a plurality of spring-controlled arms 9 so arranged as to permit the upper portion 10 of the arms to be pressed forward when a person attempts to pass the turnstile. 90

Forming a portion of the arms is a pawl 11 intended to register with a locking device 12 and adapted to render the latter inoperative when the upper-arm portion 10 is pressed forward. This locking device com-

95 pletes a lever, pivoted at 12', and provided with an inclined upper face 12'', which face is adapted to be engaged by pawls 11 of the arms. The inner portion of the lever is provided with a depression 12''' which ter-

100 minates in an abutment 112. This abutment is adapted to place itself in the path of four lugs 112', forming integral parts of rotary member 17 of the head. Lever 12 is held in

its normal upward position by a spring, not shown in the drawings. Its upward movement however is limited by the lower peripheral ledges of member 17 disposed between the four lugs 112'. The moment the inclined face of lever 12 is engaged by pawls 11, the abutment 112 of the lever is depressed below the face of the lugs 112'. The moment pressure against the arm is relieved, lever 12 assumes its normal position and is ready to engage the next following lug. By means of this locking device, the arm following the one which has been operated, is stopped from continuing the motion of the operated arm. A coil-spring 13 provided in connection with the arms (see Figure 2) causes the upper-arm portions 10 to always assume a position inclined toward the operator. The head further consists of a relatively stationary member 14 through the center of which passes a shaft 15 which is keyed to the member 14 by any suitable arrangement indicated at 15' and is thus prevented from rotating. Within the hollow part of member 14 there is provided a roller-bearing indicated at 16, upon which rests the movable member 17 of the head. Arranged about bearing 16, and depending from plate 18 of movable member 17, are a plurality of fixed detent elements, in this case rollers 19. Arranged also within the hollow part of the stationary member 14, there is a movable element of the detent, in this case a bar 20 which is held in pressing relation against rollers 19 by means of a tension spring 21. This arrangement is provided for the purpose of assuring the positioning of the movable member of the head. Keyed to shaft 15 above plate 18 of the movable head member 17, and arranged within the hollow space 17' of movable head member 17, there is arranged a friction-clutch disk 22 provided with a plurality of recesses indicated at 22', within which are lodged vertically disposed rollers 23. Against these rollers bear springs 24 so as to cause the rollers to always be in frictional engagement with the recessed portion 22' of the disk 22 and the annular surface 50 17'' of member 17. It is obvious that when member 17 is rotated in clockwise direction, rollers 23 will be pressed against springs 24 and therefore will permit the rotation of member 17. If, however, the latter is moved in opposite or anticlockwise direction, rollers 23 will be wedged between the recessed portion 22 of friction-disk 22 and the inner annular periphery of member 17, thus preventing the latter from turning. 60 Rotary member 17 is hollowed out at its upper portion as indicated at 25, and at its center forms a hub 26 provided with a bore 27 registering with vertical shaft 15 about which the member 17 rotates. At the upper 65 portion of hub 26 there is provided a gear

28 meshing with another gear 29 attached to the stationary base 30 of the counter-mechanism.

Operation.

As has been said before, my device is primarily designed for the use in street-cars. Be it however understood, that the same may be employed in any other way and at other places.

For the sake of explaining the operation of my device, I shall assume it is used in a street car where at both ends of the car are provided rigidly affixed standards near the respective entrances into which the head of my device may be readily inserted and where it may be firmly held against dislocation.

When the entering person passes into the car, the upper portion 10 of an arm 9 is pressed forward, thereby depressing lever 12 of the arm-locking mechanism. The latter is thus released and permits the rotation of the movable portion of the head. With each quarter revolution, both the totalizer and the trip-counter are operated. When the quarter revolution is completed, the detent sets the head with its arms in the proper position to receive the following person entering the car.

The detent mechanism is so arranged that when one of the rollers 19 thereof pressingly engages detent bar 20 and passes over substantially the latter's center, the spring 21, expanded by that roller 19 pressing against bar 20, causes that bar 20 to firmly press against roller 19 and causes it to assume its normal position as indicated in Figure 5.

At the same time locking lug 11 has engaged lever 12 of the locking arrangement, thus preventing the further turning of the rotary part of the head until the upper arm portion 10 of next arm is pressed against, and releases the locking lever 12.

From the foregoing, it will be evident that my device is very simple in operation and has the advantage of concentrating the entire mechanisms used in turnstiles in the removable head. This advantage becomes of great importance not only for the use of one head in a car with double standards, but also in the event that a head, for instance, would get out of order or may otherwise become inoperative. In such case, another head carried in stock may readily take the place of the defective one without entailing a loss of time due to the removal of the entire standard as has been necessary heretofore.

Another advantage of my device is its compactness and the ability of the users to store away the complete heads with the entire mechanism during the winter months when a lesser number of cars is operated. In companies using special summer and winter cars, the advantage of applying my device is very

obvious for the reason that they merely have to transfer the heads to the respective standards in the cars used at the time, thus eliminating the double purchase of expensive 5 turnstile mechanisms permanently attached to cars as was heretofore the case.

While I have shown in the drawings a specific construction of my device, be it understood that various changes and improvements 10 may be made to allow the application of my device, under various conditions, without departing from the broad scope of my invention of a removable turnstile head comprising turnstile mechanisms independent of 15 the standard in which the head operates.

Having thus described my invention, I claim:

In a portable turnstile having a stationary standard, an operating head, transferably mounted upon said standard and comprising stationary and revoluble members, a plurality of spring-controlled operating arms associated with the latter member, arm-locking means associated with the stationary member, and means forming part of the arms 25 for releasing said locking means.

Signed at New York, in the county of New York and State of New York, this 16th day of October, A. D. 1922.

DANIEL R. BACON.
